UNITED STATES PATENT OFFICE

2,413,240

MULTIPLE PUMP FOR HYDRAULIC SYSTEMS

Harold J. McGovern, Rock Island, Ill.

Original application August 3, 1942, Serial No. 453,334. Divided and this application October 17, 1944, Serial No. 559,059.

4 Claims. (Cl. 103—11)

1

My invention has reference to a pump for a hydraulic system, and is specially designed for use with a hydraulic jack or ram, such as are employed in the lifting of the truck part of a semi-trailer outfit, more specially when it is provided with a load. It involves an arrangement employing two pairs of pumps, of different capacities, and in its original showing was divided out of an application filed by applicant August 3, 1942, in the Patent Office of the United States, Serial No. 453,334, for a Pump for a hydraulic system, which later ripened into Letters Patent No. 2,337,831, under date of December 28, 1943.

One of the purposes of the invention is to have the two pairs of pumps working in unison or separately, as desired, so that when the pressure is increased to a point to make the operation difficult the use of the larger pumps can be discontinued, and additional pressure built up by the use of the smaller pumps.

There is also shown and described herein a modified and improved form of the invention, increasing the efficiency and ease of handling of the apparatus, with a means for uniting the operating devices for the pumps in a joint operation, or disconnecting the same to permit the operation of one thereof independently of the other.

The foregoing, and other features and advantages of the invention will more fully appear from the following specification, reference being had to the accompanying drawings, in which:

Fig. 1 is a plan view of a casing embodying the invention, somewhat diagrammatic, and with broken lines to indicate concealed passages.

Fig. 2 is a similar view of a modified arrangement thereof.

Fig. 3 is a fragmentary detailed showing of a part of Fig. 2, enlarged, with central parts in section.

Fig. 4 shows one of the bushings 70 in side view.

Fig. 5 is an end view thereof.

Fig. 6 is a side elevation showing one of the operating frames partly broken away.

Referring to the showing in Fig. 1, the numeral 6 indicates the upper plate of a pump casing, upon which is mounted a pair of cylinders 7 and 8, provided with piston rods 9 and 10, pivotally connected with a hand-lever 11, fixed on a post 12, fixed on a plate 13, secured to the outer face of the plate 6. Within the casing the cylinders 7 and 8 communicate with passages 14 and 15, connecting at their upper ends with a channel 16, extending lengthwise of the casing, and

2

at their lower ends with a channel 17, parallel with the first-named channel.

Entering the channel 17 at the lower side of the casing is an intake pipe 18, leading from a source of hydraulic supply, not shown in the drawings. In the upper part of the casing are outlets 19 and 20, leading from the channel 16, in which are the ends of pipes 21 and 22, leading to hydraulic jacks or other pressure control apparatus. Said pipes are provided, respectively, with cut-out valves 23 and 24 so that the flow through either one or both of said pipes can be interrupted, each of said valves being provided with a handle 25 for operation.

Also mounted on the casing 6 is a pair of cylinders 27 and 28, provided with piston rods 29, connected with pistons in the cylinders, not shown herein. The ends of said rods are pivotally connected with a hand-lever 30, fulcrumed on a post 31, also fixed on the plate 13, and parallel with the lever 11. The inner ends of the cylinders 27 and 28, the capacity of which is considerably less than that of the cylinders 7 and 8, are connected with passages 32 and 33, the ends 25 of which open into the channels 16 and 17. The lower ends of said passages are fitted with check-valves 34, and the upper ends with check-valves 35. The passages 14 and 15 are shown fitted with similar check-valve apparatus in their lower ends at 36, and in their upper ends at 36a.

The ends of the handles 11 and 30 project beyond the ends of the casing 6, and are sufficiently close together to permit the ends to be grasped by one or both hands of the operator, and the levers simultaneously rocked on their fulcrums. This results in a working of all of the pumps and rapid building up of the operative force in the casing and connected jacks. As the resistance increases there is a tendency of the pistons in the larger cylinders becoming inactive, whereupon the operation of the lever 11 is discontinued, and the pumping proceeded with by the use of the lever 30 alone, continuing the movement of the pistons in the smaller cylinders, and causing an additional movement in the pressure apparatus. The resistance of the pressure against these smaller pistons is relatively less than against the larger ones, and the operation is relatively easy.

A release means is also provided for the apparatus shown in Fig. 1, consisting of a valve casing and seat at 37, opening into a release passage 38, extending downwardly to the channel 17, and provided with a valve-stem indicated in part at

39. The valve is normally closed, but upon being opened a release of the pressure results.

The levers 11 and 30 are set forth herein as being at one side of the casing, in a horizontal position, but they are not limited to such an arrangement as the positioning can be changed, so that they will be projected above the casing, or below the same, or at either side thereof. The apparatus can be adapted for use not only with hydraulic jacks and rams, but with other structures under similar pressure control.

In Fig. 2 of the drawings the numeral 40 indicates the upper plate of a pump casing, in which is mounted a pair of cylinders 41 and 42, with piston rods 43 and 44, connected with pistons not shown in the drawings. Said piston rods are pivotally connected with a lever device consisting of a frame 45, formed of a pair of parallel spaced bars, fulcrumed at a central point on a post 46 mounted on a plate 46a secured to the plate 40. At its outer end there is fixed to the frame 45 a handle 47, by means of which said frame can be rocked on its fulcrum. The inner ends of the cylinders 41 and 42 are connected with passages 48 and 48a in the body of the casing, and the ends of said passages communicate with similar passages 49 and 50 in the body of the casing or block, shown herein in broken lines. The first-named passages are fitted with check-valves at 51 and 51a to prevent the return of hydraulic medium therethrough.

The casing 40 is also provided with a pair of cylinders 52 and 53 of larger caliber than the first-named pair of cylinders in said casing, pivotally connected with which are the outer ends of piston rods 54 and 55, connected with pistons in the last-named cylinders. The rods 54 and 55 are united by a lever formed of a pair of parallel frame pieces 56, fulcrumed on a post 57 mounted on the plate 46a. The ends of the frames 56 are united by bolts 58, with perforated spacers 59 separating the same. The inner ends of the cylinders 52 and 53 are connected with passages 60 and 61, respectively, also in communication with the passages 49 and 50, and provided with pairs of check-valves 62 and 63.

An intake pipe 64 communicates through the passage 50 with the passage 60, and is designed to conduct a supply of hydraulic medium into the interior system. Outlets 65 and 66 are provided, connecting with which are pipes 67, leading to the hydraulic system to be supplied with pressure, and provided with cut-out valves at 68. In passing to these outlets the medium passes through the several check-valves, and is restricted thereby from effecting a return movement.

It is to be noted that in the arrangement shown in Figs. 2 and 3 the cylinders of less diameter are nearer the fulcrum points than the larger ones, which results in a reduction in the piston movement and the operation of the smaller pistons when driven alone with less exertion than required for the larger ones with their increased leverage and capacity. The operation is substantially the same as set forth in said former patent. When the resistance becomes sufficiently strong the movement of the larger cylinders is halted, and the power applied to the small cylinders alone, with a further building up of the pressure.

The fulcrum supports of the frames 45 and 56 are of a special character, and consist of a pair of bushings 70 and 71, which are square in cross-section, and are provided at a central point on their outer surfaces with circular collars 72, form-

ing bearings in similarly shaped openings 73 in the posts 46 and 57. Said bushings are of hollow formation, to receive a bolt 75 of similar rectangular form, extending for the length of the bushings and compelling a joint movement of the bushings and frames upon either thereof being given a rocking movement. The bolt 75 is projected at one end into a rounded pin 76, ending in a handle 77. At the ends of said pin are washers 80 and 81, against which bear the ends of an extensible coiled spring 82, tending to hold the pin in outer position. Said spring possesses a considerable amount of flexibility, permitting the handle to be forced toward the frames until one end of the bolt clears the inner end of the bushing 70, with the other bushing and frame thereof free to be rocked independently. This is done when the pressure in the pump is at a maximum, and the use of the cylinders 52 and 53 is discontinued for the time being. By turning the handle 77 downwardly it can be engaged with the channelled upright 83a of a plate 83, fixed on the plate 40.

A screw 84 is seated in a similarly threaded opening in the end of the bolt 75 opposite to the handle 77, holding a washer 85 against the end of the bolt, and preventing its release on the handle side of the frames.

When it is desired to resume operation again with all four cylinders the handle 77 is released from the keeper, and the bolt 75 returned to its original position in both housings by the force of the spring 82.

The double form of levers 45 and 56 is found to be convenient and efficient, but the use of other forms thereof is possible, without departing from the spirit of the invention.

What I claim, and desire to secure, is:

1. In a pump for hydraulic systems, a casing 40 provided with a plurality of passages for the conduct of a quantity of hydraulic fluid, having an intake at one point in the casing, and one or more outlets opposed thereto, a pair of cylinders mounted on the casing and communicating with said system, provided with pistons and rods therefor, a hand-lever fulcrumed midway said pistons and pivoted thereto, a second pair of cylinders of smaller diameter mounted on said casing, also communicating with said system, and provided 45 with pistons and rods therefor, and a hand-lever operatively connected with said last-named rods, adapted for the independent operation of the last-named rods and pistons, the ends of said hand-levers being adapted for grasping by the hand of 55 the operator to cause a joint operation of all of said pistons during the initial operation of the device.

2. In a pump for hydraulic systems, a casing 60 provided with a plurality of passages for the conduct of a quantity of hydraulic medium, having an intake at one point in the casing and one or more outlets disposed oppositely to the intake, a pair of cylinders mounted on the casing and communicating with said system, provided with pistons and rods therefor, a lever pivotally connected with said rods, and fulcrumed intermediate the same on said casing, means for rocking said lever on its fulcrum, a second pair of cylinders mounted on the casing, varying in diameter from the first-named cylinders, also provided with pistons and piston rods therefor, a lever connecting said piston rods and fulcrumed on the casing intermediate the same, in line with the first-named fulcrum, means for locking said

levers for joint operation, releasable to permit independent operation of each thereof.

3. In a pump for hydraulic systems, a casing provided with a plurality of passages for the conduct of a supply of hydraulic medium, having an intake at one point in the casing and one or more outlets opposed thereto, check-valves in said passages preventing return movement of said medium, a pair of cylinders mounted on said casing, communicating with said system, and provided with pistons and rods therefor, a lever connecting said rods and fulcrumed on the casing intermediate the same, means for actuating said lever, a second pair of cylinders on said casing, relatively larger than the first-named pair, and provided with pistons and rods therefor, a second lever connecting said rods, and fulcrumed intermediate the same, a spring controlled lock uniting said levers for joint operation, and releasable to permit independent action of the first-named pair of pistons.

4. In a pump for hydraulic systems, a casing

provided with a plurality of passages for the conduct of a hydraulic medium, provided with an inlet at one point and one or more outlets opposed thereto, check-valves in said system preventing return of said medium, a pair of cylinders on said casing, in communication with said system, and provided with pistons and rods therefor, a lever frame connecting said piston rods, fulcrumed intermediate the same on said casing, and provided with an operator's handle, a second pair of cylinders on said casing, also communicating with said system, and provided with pistons and rods therefor, a second lever frame connected with the last-named rods, and fulcrumed intermediate 15 the same on the casing, in line with the first-named fulcrum, a bolt uniting said lever frames for joint operation, a spring yieldably connected with said bolt permitting movement thereof to free the first-named lever frame for independent 20 action, and releasable to return the same to position for joint action of said frames.

HAROLD J. McGOVERN.
